INVENTOR

UNITED STATES PATENT OFFICE.

JOHN LOWRY, OF TECUMSEH, MICHIGAN, ASSIGNOR OF ONE-HALF TO
SAMUEL MCCLURE, OF SAME PLACE.

SANDPAPERING-MACHINE.

SPECIFICATION forming part of Letters Patent No. 543,878, dated August 6, 1895.

Application filed July 25, 1894. Serial No. 518,511. (No model.)

To all whom it may concern:

Be it known that I, JOHN LOWRY, a citizen of the United States, residing at Tecumseh, county of Lenawee, State of Michigan, have 5 invented a certain new and useful Improvement in a Sandpapering-Machine; and I declare the following to be a full, clear, and exact description of the invention, such as will enable others skilled in the art to which it applies to make and use the same, reference being had to the accompanying drawings, which form a part of this specification.

My invention has for its object a sandpapering-machine for sandpapering door-panels, 15 the purpose of my invention being to produce a machine whereby the raised face of the panel, together with the beveled faces and rabbeted surfaces, may all be sandpapered on one side of the panel in one operation.

20 My invention consists of the construction, combination, and arrangement of devices hereinafter described and claimed, and illustrated in the accompanying drawings, in which—

25 Figure 1 is a side elevation embodying my invention, showing a part in section. Fig. 2 is a plan of the same. Fig. 3 is a detail view in horizontal section on the line 3 3, Fig. 1, showing the mechanism for laterally adjusting the cutter-head. Fig. 4 is a vertical section through the drum. Fig. 5 is a vertical section through the horizontally-rotatable heads, showing parts in elevation. Fig. 6 is a detail view, partly in vertical section and 35 partly in elevation, showing the mechanism for adjusting the drum.

I carry out my invention as follows:

A represents any suitable supporting-frame. B denotes a driving-shaft provided with 40 ordinary fast and loose pulleys b b' . The shaft is journaled in suitable boxes A' and A'' engaged upon the frame. As shown, the driving-shaft is provided with two driving-pulleys B' and B'' .

45 C is a drum mounted upon a shaft C' , suitably journaled in the frame A. This drum may be vertically adjusted in any suitable manner. I design to provide the drum either with a sandpaper surface or with a sand belt, 50 as may be desired, a sand belt being shown

in dotted lines, Fig. 1, at F, the belt being carried from the drum C over an additional drum C'' . If, however, it be preferred to dispense with the sand belt and to provide the surface of the drum with sandpaper or analogous material, the paper may be fastened thereupon in any suitable manner, but preferably as hereinafter explained. The shaft of the drum is provided with a pulley C' , belted with the pulley B' upon the driving-shaft. 60

G denotes a vertical rotatable shaft journaled at one end of the frame, as shown, said shaft bearing toward its upper end sandpapering-heads G' and G'' , spaced the one from the other, said heads being so constructed and 65 arranged as to sandpaper the beveled and rabbeted surfaces of the panel. The shaft G is made vertically adjustable in any suitable manner, as by means of an adjusting-screw G^3 . Upon the shaft G is a driving-pulley G^4 70 belted with the pulley B' upon the driving-shaft.

H is an additional rotatable shaft suitably journaled upon the frame, carrying a cutter-head H' at its upper end. This shaft is made 75 vertically adjustable in any suitable manner, as by means of an adjusting-screw H^2 . Upon the shaft H is a pulley H^3 , over which is passed the belt B^3 , by which the pulleys G^4 and B' are belted together. It will be observed by 80 reference to Fig. 2 that on account of the location of the shaft H of the cutter-head H' the shaft G of the sandpaper heads G' G'' is at one side of the driving-pulley B' . The belt B^3 is accordingly diverted, so as to pass properly 85 about the pulley G^4 , the belt being diverted about the pulley H^3 of the shaft H, the diversion of the belt serving at the same time to rotate the pulley H^3 .

In order that the drum C may be readily accessible I prefer to provide the top of the frame A with a table A^3 , hinged to the frame, as shown at a, and which may be turned over out of the way when desired, said table being turned out of the way, as illustrated in Fig. 2. 90 95

C^4 denotes a sandpaper or other suitable covering for the drum C, which I prefer to engage upon the drum in the following manner:

C^5 and C^6 denote blocks engaged in the rim 100

of the drum, between which are engaged clamping-arms E and E', having a wedged engagement between said blocks.

E² denotes a turnbuckle, by which the 5 clamping-arms E E' may be tightened. The covering C⁴ has its meeting edges turned in between said clamping-arms and engaged thereby in such a way that when the clamping-arms are tightened up the edges of the 10 covering will be clamped firmly therebetween, and at the same time the covering will be stretched snugly and firmly upon the drum. The turnbuckle may be connected with the clamping-arms in any suitable manner, as by 15 means of a rod E³, which may have the turnbuckle interposed therein, one end thereof being engaged about the shaft C'.

I do not limit myself to any definite construction of the cutter-head H'. The purpose 20 of the cutter-head is to cut away the corners of the panel slightly to facilitate the entrance of the rabbeted edges into place in making up the door. The cutter-head is preferably of oblong form, as shown more particularly in 25 Fig. 2.

To adjust the cutter-head vertically the lower end of the shaft H may rest in a support h, the adjusting-screw H² being engaged in the base of said support to bear upon the 30 lower end of the shaft H.

To adjust the cutter-head laterally the support h may be provided with an arm h' extended through the side of the frame of the machine, its extremity being provided with 35 an adjusting-screw h². An additional arm h³ projects through a slot a' in the frame, the elongated slot allowing a lateral movement of the arm h³. A nut h⁴ enables the arm h³ to be tightened rigidly in any given position 40 of lateral adjustment.

The drum C may be vertically adjusted in the following manner: J denotes a hanger or bracket engaged upon the frame A, through 45 which is projected an adjusting-screw K, having a screw-threaded connection in the hanger, as shown at j. The upper end of the adjusting-screw K is provided with arms k and k', projecting upward adjacent to the boxing L of the shaft C', which boxing may be provided with laterally-projected hubs l. The boxing L is carried upon adjusting-screws M and M' passed through the upper ends of the arms k k'. By means of the screws M and M' the shaft C' may be adjusted laterally, while 50 by means of the screw-threaded engagement of the screw K in the hanger, as at j, the shaft C' may be adjusted vertically, as may be required.

The shaft G may be adjusted vertically by 60 engaging its lower end in a support g provided with an adjusting-screw G³ having a screw-threaded connection therewith, a spring g' being preferably interposed between the adjacent ends of the shaft G and screw G³. The sandpaper heads G' G² may be constructed in any suitable manner, but prefer-

ably each with a rim g² beveled upon its periphery, the head G' being beveled on its lower face and the head G² being beveled on its upper face, as shown at g³ and g⁴. Each 70 of the heads is preferably formed with a metallic head G⁵, having a screw-threaded connection within the corresponding rim g².

P denotes a conical-shaped block having a dovetailed engagement within the rim g². 75 Over the block P is engaged the sandpaper or other analogous covering p. By tightening the head G⁵ against the corresponding block the covering p is held tightly over the block.

The operation of my device is as follows: 80 The drum C polishes the raised face of the panel. When the panel is run through the machine on one side, the corresponding raised face is brought into contact with the drum C. At the same time the upper and under rabbeted faces and beveled faces on two edges of the panel are simultaneously polished between the heads G' G², the rabbeted faces projecting between the horizontal faces of the blocks P P, while the beveled faces of the 85 blocks P P polish the beveled faces of the panel. We thus have one raised face on the upper and lower rabbeted faces and upper and lower beveled faces at two edges of the panel all polished in one operation. The 90 panel is then turned over and at right angles to its former position and again run through the machine, by which second operation the raised face on the opposite side of the panel and the rabbeted and beveled faces on the 95 other two edges of the panel on the upper and lower sides are simultaneously polished, completing the operation.

It will be seen that the device is simple in its construction and operation, while at the 100 same time of superior efficiency.

I prefer that the shaft G should have a slight connection with the heads G' and G², the shaft having a yielding vertical movement therethrough by means of the spring 110 g', so that the heads G' G² may give, as occasion may require, for panels of unequal width at their rabbeted edges or for any inequalities on the rabbeted surfaces of the panels.

I prefer that the drum C and the blocks C⁵ 115 C⁶ should have an outer covering N of carpeting or analogous material.

Figs. 1 and 2 show a hanger J at one end of the shaft C'. The opposite end of the shaft is supported in a similar manner.

My invention contemplates having the two sandpapering heads G' and G² adjustable upon the shaft G, the one being adjustable independent of the other. This I accomplish by providing the head G' with a cap G⁶, having a screw-threaded connection with the head G⁶, said cap being held upon the shaft G by means of a nut g⁶. It will be evident that by adjusting the screw-threaded connection of the cap G⁶ with the metallic head G⁵ the head 120 G' as a whole will be adjusted upward or downward, as may be required. The metallic

head G⁵ in the head G² may be formed with a hub G⁹, through which the shaft is sleeved, a set-screw g⁷ permitting the adjustment of the head G² on the shaft.

5 What I claim as my invention is—

1. The sandpapering drum C herein described, provided with the blocks C⁵, C⁶ engaged in the rim of the drum, clamping arms E, E' having a wedged engagement between said blocks and means for tightening said clamping arms, substantially as set forth.
2. The sandpapering drum C provided with the blocks C⁵ C⁶ engaged in the rim of the drum, clamping arms E, E', means for tightening said clamping arms having a wedged

engagement between said blocks and a sandpaper or analogous covering about said cylinder having its edges engaged between said clamping arms, substantially as set forth.

3. In combination, a rotatable shaft and the sandpapering heads G', G², said shaft having a yielding vertical movement and made vertically adjustable, substantially as set forth.

In testimony whereof I sign this specification in the presence of two witnesses.

JOHN LOWRY.
